UNITED STATES PATENT OFFICE.

ELIZABETH HARRISON LEWIS, OF WHITE SULPHUR, WEST VIRGINIA.

DESIGN FOR A DOLL.

49,064.

Specification for Design.

Patented May 16, 1916.

Application filed March 9, 1916. Serial No. 83,200. Term of patent 7 years.

To all whom it may concern:

Be it known that I, ELIZABETH HARRISON LEWIS, a citizen of the United States, residing at White Sulphur, Greenbrier county, and State of West Virginia, have invented a certain new, original, and ornamental Design for a Doll, of which the following is a specification.

The design of the doll is illustrated in the drawing which is made a part hereof and to which reference is made.

The dress is intended to be of leather, or buckskin, and buff in color. The band around the head is likewise of buff material and ornamented with beads or stones of various colors. The string of beads around

the neck and falling down over the front of the dress is also made of various colored stones, or other substances. The slippers, or moccasins, are likewise decorated with beads of various colors.

What I claim is:

The ornamental design for a doll as herein shown and described.

In witness whereof, I have hereunto set my hand and seal at Washington, District of Columbia, this seventh day of March, A. D. nineteen hundred and sixteen.

ELIZABETH HARRISON LEWIS. [L. S.]
